UNITED STATES PATENT OFFICE.

ADOLPH H. DAUS, OF CHICAGO, ILLINOIS.

SAFETY APPLIANCE FOR ELECTRIC-RAILWAY TRAINS.

No. 892,712.

Specification of Letters Patent.

Patented July 7, 1908.

Application filed December 2, 1907. Serial No. 404,794.

To all whom it may concern:

Be it known that I, ADOLPH H. DAUS, a citizen of the United States, residing at Chicago, in the county of Cook and State of Illinois, have invented a certain new and useful Improvement in Safety Appliances for Electric-Railway Trains, of which the following is a full, clear, concise, and exact description, reference being had to the accompanying drawings, forming a part of this specification.

It is an object of my invention to provide improvements in interlocking safety devices on cars electrically driven, to prevent accidents resulting from the brakes being in a condition to prevent control of the train.

My invention is particularly applicable to systems of train operation in which one or more cars of the train are equipped with electric motors for driving such cars and these motors are jointly controlled from a master controller located as desired on the train.

In common practice several of the cars of the train may be provided with such master controllers, and whether there is a motor on one car only or there are motors on several of the cars, the control exercised from each of the controllers governs all of the motors.

In systems of this character, air brakes are usually employed to stop the train, and my invention specifically consists in means associated with the controlling valves of such air brake system by which, if such valves are not properly set to permit the operation of the brakes, the control exercised by the controllers is interrupted and can only be restored by properly setting such valves.

In systems of control of the class above described, it is usual to run controlling leads through the train and to connect these leads to the several controllers, such leads being connected to the electromagnetic mechanism employed to operate the motor, or, in case several motors are in operation on the train, a plurality of such electromagnetic mechanisms are thus connected. An air controlling valve is usually associated with each controller and my invention in its simplest form consists in switching means associated with each of such valves for interrupting the main operating circuit of the associated controller if the valve is in a position to prevent applying the brakes, and for closing a low resistance path between the controlling leads used to control the main operating circuit of

the motor or motors when the valve is in a position to permit the operation of the brake mechanism. As long as this path is closed all other controllers on the train are rendered inoperative. Thus it will be seen I have necessitated by my invention, for rendering any controller operative, that the valve associated therewith must be in a position to permit the operation of the brake mechanism and all the other valves must be in a position to prevent the operation of such mechanism from the location of the other controllers, which is a condition always to be desired.

One of the particular objects of my invention is to utilize the circuits which are employed in the control of the motor or motors for the operation of the interlocking safety devices of this invention. Thus, my invention does away with the necessity for any circuits in addition to those already required for the operation of electric cars or trains. In the preferred embodiment of my invention as herein disclosed, the operation of the motors depends upon any difference in potential in two wires extending through the car or cars of a train. My present invention provides for the short-circuiting of these wires or conductors whenever the air brake controlling mechanism is not in a proper condition for the contemplated operation of the train.

Other features of my invention not here specifically indicated, will appear from the description below.

The several drawings illustrating my invention are as follows: Figure 1 shows in diagrammatic view the operating mechanism for controlling the motors on a train, and associated therewith air brake operating mechanism adapted to embody my invention; Figs. 2 and 3 are detailed front and top views of devices which I preferably attach to one of the air pipes of the braking system to coöperate with a valve in such pipe for accomplishing the results to be described; Fig. 4 shows in detailed sectional view a modified form of operating mechanism for the main switch of the main motor circuit, and Fig. 5 shows in detailed sectional view a modified form of air controlled switching mechanism for insuring proper working conditions in the air brake system before the car can be operated.

Referring to Fig. 1, it will be noticed that several sets of identical mechanism are indicated, that is, a controller C and brake con-

trolling mechanism V, represented as associated with each end of each of two cars, the dividing line between such cars being indicated by the dotted line x, y .

5 The system of control herein represented is that well known in the art, in which a master controller located at either end of any car in a train may control switching mechanism for regulating the speed of a motor on one of such cars or motors on several of such cars. 10 As shown in the drawings, 10, 11 and 12 are conductors arranged to extend throughout the train, being connected from car to car by jumper connections, as shown, and from 15 these conductors connections are made to the controller C, as indicated. This controller consists of several movable contact sections, as c , c^1 , and c^2 electrically connected and arranged in accordance with ordinary 20 construction to move together. Another section c^3 is also adapted to be moved with the sections just mentioned. These several sections are arranged to make contact with a 25 number of contact points when such sections are moved in the operation of control, and in a manner well known in the art the several circuits closed by such operation are adapted to operate switching mechanism for controlling the driving motors of the car, as a result 30 of which controller C controls these motors and therefore the motion of the car. In this connection, we are concerned with but one of the circuits controlled by the controller C, this being a circuit adapted to operate the 35 main switch of the motor controlling mechanism by which an operative circuit is closed through the driving motors, after which the controller further operates to establish various speed conditions of such motors, as desired. A storage battery B is usually 40 connected, as indicated, between conductors 11 and 12 to operate the switching mechanism.

When the controller C is moved so as to 45 bring the section c^2 into engagement with the contacts 3 and 4, assuming that the line switch s is thrown in the position shown in dotted lines, a circuit is closed as follows: Battery B, conductor 11, wire 6, contact 16, 50 switch 17, contact 15, wire 5, contact 4, section c^2 , contact 3, wire 14, resistance r , contact 13, switch s , wire 9, contact 18, switch s^1 , contact 19, wire 8, conductor 10, wire 28, solenoid 27, wire 29, conductor 12 back to 55 battery B. For this position of the controller C it will be understood the section c^3 is moved out of engagement with the contacts 1 and 2, so that connection between wires 7 and 9 is opened. As a result of the circuit 60 above described, the solenoid 27 is energized by which the core 26 is drawn downwardly against the resistance of the spring 45, closing switch s^2 and an operating circuit through the motors as follows: third rail shoe s^3 , wire 65 24, switch s^2 , contact 25, resistance r^1 and

thence in series through the motors M, M and field windings f, f to ground back to the source of energy used to drive the cars. The spring 45 serves to return the core 26 to its normal position and to thereby open the 70 switch s^2 when the solenoid 27 is not energized. A trolley T is shown as connected to the wire 24 in order that power may be taken from an overhead trolley instead of a third rail, if desired. The closing of the circuit 75 through the motors results in starting the same, and by successive positions of the controller C the value of the resistance r^1 may be varied as desired, and other changes in the 80 relations of the motors M, M to the operating circuit may be effected in any well-known way familiar to those versed in the art.

The air brake controlling system shown in connection with this invention consists in a motor M^1 adapted to drive an air pump P 85 connected to an air tank R and supply pipe p for furnishing air as required to operate the braking mechanism. This pipe p extends throughout the train, as does a second pipe p^1 known as the train pipe. Connections are 90 made from the pipes p and p^1 at each position of control by pipes p^2 and p^3 respectively, through valves v and v^1 to a controlling valve of a type well known in the art. A third pipe p^4 , known as the exhaust pipe, is also 95 connected to this operating valve. A valve v^2 is connected with the train pipe p^1 and there are also connected to this valve v^2 an air tank R^1 and operating cylinder 23 for operating the brakes. The valve v^2 is adapted 100 to be operated in such a manner that when the pressure in the pipe p^1 reaches a certain amount this valve is operated to open a passageway between the pipe p^1 and tank R^1 . This condition is maintained as long as the 105 pressure in the pipe p^1 is maintained, and when the air is permitted to escape from the pipe p^1 and the pressure is thereby diminished below a certain predetermined amount, the valve v^2 operates to form a passage between the tank R^1 and the cylinder 23, as a 110 result of which the air in the tank R^1 serves to set the brakes in a manner well known. When the pressure in the pipe p^1 is again increased to the amount required to operate 115 the valve v^2 , connection is again established between the pipe p^1 and the tank R^1 through such valve and an exhaust passage is opened from the cylinder 23 by which the brakes are released.

In order to provide that the conditions in the air brake system shall be proper for operating the train, I make use of a switch s^1 associated with the operating handle of the valve v^1 by which, when the valve v^1 is in a position 125 to open the pipe p^3 to the operating valve, connection will be established between the contacts 18 and 19 and therefore the operating circuit through the solenoid 27 will be established upon actuation of the controller C 130

in the manner already described. From this it will be seen that if the valve v^1 is not in an open position so that air can be supplied from the supply pipe p to the train pipe p^1 , the controller C is rendered inoperative by the opening of its circuit between contacts 18 and 19. It is to be noted in this connection that there is also a valve v located in the supply pipe and that the operating handles on valves v and v^1 are so related that the valve v must be opened before the valve v^1 can be opened, and hence the switch s^1 constitutes a means by which both of these valves must be in open or operative position, that is, a position to permit the operation of the brake mechanism, in order to complete the operating circuit of the controller.

As shown diagrammatically in connection with the supply pipe p^2 , an air operated mechanism is made use of to control the switch 17 as a result of which, if the air pressure in the supply pipe is not sufficient to operate the brake mechanism, the switch 17 is maintained in open position and is not closed until the air pressure has been increased sufficiently to operate the brake mechanism, for which condition the switch 17 is closed. This mechanism consists of a cylinder 20 in which a piston 21 is adapted to move against the resistance of a spring 22. The switch 17, as indicated, is connected to the piston 21, so that movement of the piston by the air pressure in the cylinder will operate such switch. The spring 22 is adjusted for the air pressure used in the supply pipe to cause the piston and associated switch to operate as indicated above. As shown in Fig. 5, the tension of the spring 22 may be regulated by means of the threaded plug 30 in the end of the cylinder to provide for adjusting this switch mechanism for various air pressures.

My system includes a further protective feature, as a result of which, if the air controlling valves are not left in a position to permit the operation of the air brake mechanism from another location on the train, the solenoid 27 will be rendered inoperative, thus indicating that at some point the relation of the valves is not right and requiring the proper adjustment of such valves before the train can be started. This condition may be illustrated with regard to the controller C as follows: The controller is shown in normal or neutral position, that is, the position in which it is left when it is desired to operate the train from one of the other controllers. For this condition the valves v and v^1 should occupy a vertical position in order to shut off the pipes p^2 and p^3 and thus positively prevent improper opening of the train pipe p^1 or the supply pipe p by means of the operating valve associated with the controller C. In the event, however, of the valves being carelessly or maliciously moved to a position

to open the pipes p^2 and p^3 , whether the operating valve is moved to a position to improperly operate the system or not, the switch s^1 is moved to a closed position, as a result of which a circuit is closed as follows. Conductor 12, wire 7, contact 1, section c^3 , contact 2, wire 9, contact 18, switch s^1 , contact 19, wire 8, conductor 10, that is, a circuit of very low resistance is closed across the conductors 10 and 12, and hence this path of low resistance will take any current delivered to the conductors 10 and 12 by another of the controlling mechanisms, instead of such current going through solenoids 27 to operate the same, and hence for this condition the solenoids 27 are rendered inoperative.

I have above described in detail the controlling mechanism for but one end of one car, and this description applies equally to the other controlling mechanisms used, as well as to the brake and motor mechanism indicated on the second car and hence no detailed description of these other controlling and operating mechanisms is necessary.

As shown in Fig. 1, the controllers C^1 , C^2 and C^3 are in neutral position and the valves in the supply and train pipe connections are in closed position, while the line switches at the controller are open, all of which should be to properly control the train from the controller C.

In Figs. 2 and 3, I have shown in detail one form of construction of the switch s^1 and means for securing such switch to the pipe p^3 . A supporting member 38 is arranged to carry the base 39 of insulating material to which contacts 18 and 19 are secured. This supporting member 38 is adapted to be clamped to the pipe p^3 by a clip 37, as indicated. A lever 36 pivoted at 40 to the base 39 has secured thereto by insulating means, the switch member s^1 adapted to engage the contacts 18 and 19 or to be disengaged therefrom as such lever is moved upon its pivot. This lever has formed in its outer end a slot, as indicated, to engage a screw 35 secured in the operating handle 34 of the valve v^1 as a result of which when the handle 34 is moved from the position indicated to a vertical position the lever 36 is moved upon its pivot 40 so as to disengage the switch s^1 from the contacts 18 and 19.

In Fig. 4, I have shown a modified form of mechanism for operating the main switch s^2 in which the solenoid 27 is adapted to operate a needle valve 44 by means of a core 42 and to thereby open connection from a pipe p^5 adapted to be connected with the supply pipe p , the air pressure thus admitted by the valve serving to move the piston 32 in the cylinder 31 against the tension of the spring 33. A spring 43 is provided to insure the closing of the valve 44 when the solenoid 27 is not energized. After the switch s^2 is actuated by this means when the solenoid 27 is

deenergized, the valve 44 is returned to its seat and an exhaust passage 41, which is closed by the valve 44 in its operative position, is opened to permit the air in the cylinder 31 to escape and to permit the spring 33 to move the switch s^2 to its open position.

While I have shown my invention in the particular embodiment herein described, I do not, however, limit myself to this construction but claim all equivalent constructions and modifications that will readily suggest themselves to those skilled in the art.

1. In combination with a car adapted to be electrically driven, a motor therefor, means for supplying electric energy from feeders to the operating circuit of such motor, switching mechanism for controlling such circuit, electromagnetic mechanism adapted to control such switching mechanism, a controller on such car adapted to control the energizing circuit of such electromagnetic mechanism, brake mechanism carried by such car, operating means for such brake mechanism, and means associated with such operating means for closing a low resistance path between the terminals of such electromagnetic mechanism when such operating means is in a condition to permit the operation of such brake mechanism.

2. In combination with a car adapted to be electrically driven, a motor therefor, means for supplying electric energy from feeders to the operating circuit of such motor, switching mechanism for controlling such circuit, electromagnetic mechanism adapted to control such switching mechanism, two controllers on such car each adapted to control the energizing circuit of such electromagnetic mechanism, brake mechanism carried by such car, operating means for such brake mechanism associated with each controller, and means associated with each of such operating means for closing a low resistance path between the terminals of such electromagnetic mechanism when such operating means is in a condition to permit the operation of such brake mechanism.

3. In combination with a car adapted to be electrically driven, a motor therefor, means for supplying electric energy from feeders to the operating circuit of such motor, switching mechanism for controlling such circuit, electromagnetic mechanism adapted to control such switching mechanism, two controllers on such car each adapted to control the energizing circuit of such electromagnetic mechanism, brakes carried by such car, mechanism for pneumatically operating such brakes, a valve associated with each controller, each of such valves adapted to control the operation of such pneumatic mechanism, and a switch associated with each valve for closing a low resistance path between the terminals of such electromagnetic mechanism when such valve is in a po-

sition to permit the operation of such brake mechanism.

4. In a system of train control, a plurality of cars, an electric motor carried by one of such cars, means for supplying electric energy to the operating circuit of such motor, switching mechanism for controlling such circuit, electromagnetic mechanism adapted to control such switching mechanism, a controller on each of such cars adapted to control the energizing circuit of such electromagnetic mechanism, brakes carried by such cars, mechanism for pneumatically operating such brakes, a valve for controlling the operation of such pneumatic mechanism, and means associated with such valve for closing a low resistance path between the terminals of such electromagnetic mechanism when such valve is in a position to permit the operation of such brakes.

5. In a system of train control, a plurality of cars, an electric motor carried by one of such cars, means for supplying electric energy to the operating circuit of such motor, switching mechanism for controlling such circuit, electromagnetic mechanism adapted to control such switching mechanism, a controller on each of such cars adapted to control the energizing circuit of such electromagnetic mechanism, brakes carried by such cars, mechanism for pneumatically operating such brakes, a valve for controlling the operation of such pneumatic mechanism, means associated with such valve for closing a low resistance path between the terminals of such electromagnetic mechanism when such valve is in a position to permit the operation of such brakes, and means for opening the operative circuit of such controller when such valve is in a position to prevent the operation of such brakes.

6. In a system of train control, a plurality of cars, an electric motor carried by one of such cars, feeders adapted to supply electric energy to the operating circuit of such motor, switching mechanism on one of such cars for controlling such circuit, conductors extending through the train, an electromagnetic mechanism bridged between two of such conductors and adapted to control such switching mechanism, a controller on another of such cars for operating such electromagnetic mechanism, brakes carried by such cars, mechanism for pneumatically operating such brakes, a valve associated with such controller and adapted to control such pneumatic mechanism, and a switch operated by such valve and adapted to be moved to a position to close a low resistance path between such two conductors when such valve is in a position to permit the operation of such brakes.

7. In a system of train control, a plurality of cars, an electric motor carried by each of such cars, feeders adapted to supply electric

- energy to the operating circuits of such motors, switching mechanism for controlling such circuits, conductors extending through the train, an electromagnetic mechanism 5 bridged between two of such conductors and adapted to control such switching mechanism, a controller on each of such cars adapted to operate such electromagnetic mechanism, brakes carried by such cars, mechanism for 10 pneumatically operating such brakes, a valve associated with each controller and adapted to control such pneumatic mechanism, and a switch operated by each valve, each of such switches adapted to close a low 15 resistance path between such two conductors when the associated valve is in a position to permit the operation of such brakes.
8. In a system of train control, a plurality of cars, an electric motor carried by each of 20 such cars, feeders adapted to supply electric energy to the operating circuits of such motors, switching mechanism for controlling such circuits, conductors extending through the train, an electromagnetic mechanism 25 bridged between two of such conductors and adapted to control such switching mechanism, a controller on each of such cars adapted to operate such electromagnetic mechanism, brakes carried by such cars, mechanism for 30 pneumatically operating such brakes, a valve associated with each controller and adapted to control such pneumatic mechanism, and a switch operated by each valve, each of such switches adapted to close a low resistance 35 path between such two conductors when the associated valve is in a position to permit the operation of such brakes, and each of such switches adapted to open the operative circuit of the corresponding controller when the 40 associated valve is in a position to prevent the operation of such brakes.
9. In an electric car, the combination of one or more electric motors for driving the car, two motor controllers on said car, a common 45 motor controlling circuit leading to said motor controllers, a brake system, a brake controlling device associated with each motor controller, and switching mechanism mechanically operated by said brake controlling 50 devices and operating upon said motor controlling circuit to render either electric motor controller inoperative when the brake controlling devices are not in their proper position for the control of the car by that motor 55 controller.
10. In an electric railway train, the combination of one or more electric motors for driving the train, a plurality of motor controllers, a common motor controlling circuit 60 leading to said motor controllers, a brake system, a brake controlling device associated with each motor controller, and switching apparatus operated by said brake controlling devices to render the common motor controlling circuit inoperative in response to the ac- 65

tuation of any one of said controllers when the brake controlling devices are not in proper position for the control of the train by that motor controller.

11. In an electric motor driven railway 70 train, the combination of a brake system, a plurality of brake controlling devices located at different points on said train, a plurality of electric motor controllers located at different points on said train, a common motor 75 control circuit leading to all of the motor controllers, and means associated with each brake controlling device to render the motor controlling circuit inoperative whenever such brake controlling device is in a condition 80 to prevent setting the brakes.

12. In an electric motor driven railway train, the combination of a brake system, a plurality of brake controlling devices located at different points on said train, an electric 85 motor controller associated with each of the brake controlling devices, a common motor control circuit leading to all of the motor controllers, and switching mechanism associated with each of said brake controlling devices 90 and connected with said common motor control circuit for rendering the common motor control circuit inoperative whenever any of the brake controlling devices is in a condition to prevent setting the brakes. 95

13. In an electric motor driven railway train, the combination of a brake system, a plurality of brake controlling devices located on said train, a plurality of electric motor controllers located on said train, a common motor control circuit leading to all of the motor controllers, electromagnetic switching apparatus connected with the common motor control circuit for governing the supply of current to the motor or motors, and switching mechanism associated with each of said brake controlling devices and connected with said common motor control circuit for rendering the common motor control circuit impotent to actuate the electromagnetic switching apparatus when any of the brake controlling devices is in a condition to release the brakes. 100 105 110

14. In an electric railway car, the combination of a motor controlling circuit, a brake 115 system, a brake controller, and a switching device electrically connected with the motor controlling circuit and mechanically connected for actuation by the brake controller.

15. In an electric railway car, the combination of a motor controlling circuit, a brake system, a brake controller, and a self contained switching device electrically connected with the motor controlling circuit and detachably secured to the mechanism of the 125 brake controller for actuation thereby.

16. In combination with a car adapted to be electrically driven, a motor therefor, means for supplying electric energy from feeders to the operating circuit of such mo- 130

tor, switching mechanism for controlling such circuit, two controllers on such car each adapted to operate such switching mechanism, brake mechanism carried by such car, 5 operating mechanism for such brake mechanism, and means associated with such operating means for rendering such switching mechanism inoperative by circuits adapted to be closed through the motor controlling 10 circuit, such condition adapted to be produced when such operating means is in a condition to permit the operation of such brake mechanism.

17. In combination with a car adapted to
15 be electrically driven, a motor therefor,
means for supplying electric energy from
feeders to the operating circuit of such mo-
tor, switching mechanism for controlling
such circuit, two controllers on such car each
20 adapted to operate such switching mech-
anism, brakes carried by such car, mechanism
for pneumatically operating such brakes, a
valve for controlling the operation of such
pneumatic mechanism, and means associated
25 with such valve for rendering such switching
mechanism inoperative by circuits adapted
to be closed through the motor controlling
circuit, such condition adapted to be pro-
duced when such valve is in a position to per-
30 mit the operation of such brake mechanism.

30 18. In combination with a car adapted to
be electrically driven, a motor therefor,
means for supplying electric energy from
feeders to the operating circuit of such mo-
35 tor, switching mechanism for controlling
such circuit, two controllers on such car each
adapted to operate such switching mech-
anism, brakes carried by such car, mechanism for
pneumatically operating such brakes, a valve
40 associated with each controller, each of such
valves adapted to control the operation of
such pneumatic mechanism, and means as-
sociated with each of such valves for render-
ing such switching mechanism inoperative
45 by circuits adapted to be closed through the
motor controlling circuit, such condition
adapted to be produced when such valve is in
a position to permit the operation of such
brake mechanism.

50 19. In combination with a car adapted to be electrically driven, a motor therefor, means for supplying electric energy from feeders to the operating circuit of such motor, switching mechanism for controlling
55 such circuit, electromagnetic mechanism adapted to control such switching mechanism, two controllers on such car each adapted to control the energizing circuit of such electromagnetic mechanism, brake mechanism
60 carried by such car, operating means for such brake mechanism associated with each controller, and means associated with each of such operating means for rendering such electromagnetic mechanism inoperative by circuits adapted to be closed through the motor
65

controlling circuit, such condition adapted to be produced when such operating mechanism is in a condition to permit the operation of such brake mechanism.

20. In combination with a car adapted to 70
be electrically driven, a motor therefor,
means for supplying electric energy from
feeders to the operating circuit of such motor,
switching mechanism for controlling such circuit, electromagnetic mechanism 75
adapted to control such switching mechanism,
two controllers on such car each adapted to control the energizing circuit of such electromagnetic mechanism, brakes carried by such car, mechanism for pneumatically 80
operating such brakes, a valve associated with each controller, each of such valves adapted to control the operation of such pneumatic mechanism, and a switch associated with each of such valves for rendering 85
such electromagnetic mechanism inoperative by circuits adapted to be closed through the motor controlling circuit, such condition adapted to be produced when such valve is in a position to permit the operation of such 90
brake mechanism.

21. In a system of train control, a plurality of cars, an electric motor carried by one of such cars, means for supplying electric energy to the operating circuit of such motor, switching mechanism for controlling such circuit, electromagnetic mechanism adapted to control such switching mechanism, a controller on each of such cars adapted to control the energizing circuit of such electromagnetic mechanism, brakes carried by such cars, mechanism for pneumatically operating such brakes, a valve for controlling the operation of such pneumatic mechanism, and means associated with such valve for rendering such electromagnetic mechanism inoperative by circuits adapted to be closed through the motor controlling circuit, such condition adapted to be produced when such valve is in a position to permit the operation of such brake mechanism. 110

22. In a system of train control, a plurality of cars, an electric motor carried by one of such cars, means for supplying electric energy to the operating circuit of such motor, switching mechanism for controlling such circuit, electromagnetic mechanism adapted to control such switching mechanism, a controller on each of such cars adapted to control the energizing circuit of such electromagnetic mechanism, brakes carried by such cars, mechanism for pneumatically operating such brakes, a valve for controlling the operation of such pneumatic mechanism, means associated with such valve for rendering such electromagnetic mechanism inoperative by circuits adapted to be closed through the motor controlling circuit, such condition adapted to be produced when such valve is in a position to permit the operation 115 120 125 130

of such brake mechanism, and means for opening the operative circuit of the associated controller when such valve is in a position to prevent the operation of such 5 brakes.

23. In a system of train control, a plurality of cars, an electric motor carried by one of such cars, feeders adapted to supply electric energy to the operating circuit of such 10 motor, switching mechanism on one of such cars for controlling such circuit, conductors extending through the train, an electromagnetic mechanism in circuit with such conductors and adapted to control such switching 15 mechanism, a controller on another of such cars for operating such electromagnetic mechanism, brakes carried by such cars, mechanism for pneumatically operating such brakes, a valve associated with such controller and adapted to control such pneumatic mechanism, and a switch operated by such valve and adapted to render such electromagnetic mechanism inoperative by circuits closed through the conductors used in 20 operating such electromagnetic mechanism, such condition adapted to be produced when such valve is in a position to permit the operation of such brakes.

24. In a system of train control, a plurality of cars, an electric motor carried by each of such cars, feeders adapted to supply electric energy to the operating circuits of such 30 motors, switching mechanism for controlling such circuits, conductors extending through the train, an electromagnetic mechanism in circuit with such conductors and adapted to control such switching mechanism, a controller on each of such cars adapted to operate such electromagnetic mechanism, brakes carried by such cars, mechanism for pneumatically operating such brakes, a valve associated with each controller and adapted to control such pneumatic mechanism, and a switch operated by each valve, each of such 40 switches adapted to render such electromagnetic mechanism inoperative by circuits closed through the conductors used in operating such electromagnetic mechanism, such condition adapted to be produced when the 45 valve associated with such switch is in a position to permit the operation of such brakes.

25. In a system of train control, a plurality of cars, an electric motor carried by each of such cars, feeders adapted to supply electric energy to the operating circuits of such 55 motor, switching mechanism for controlling such circuits, conductors extending through the train, an electromagnetic mechanism in circuit with such conductors and adapted to control such switching mechanism, a controller on each of such cars adapted to operate such electromagnetic mechanism, brakes carried by such cars, mechanism for pneumatically operating such brakes, a valve associated with each controller and adapted to 60

control such pneumatic mechanism, and a switch operated by each valve, each of such switches adapted to render such electromagnetic mechanism inoperative by circuits closed through the conductors used in operating such electromagnetic mechanism, such condition adapted to be produced when such switch is in a position to permit the operation of such brakes, each of such switches adapted to open the operative circuit of the 70 corresponding controller when the associated valve is in a position to prevent the operation of such brakes.

26. In combination with a car adapted to be electrically driven, a controller for operating the car, electromagnetic mechanism to be operated by such controller in such operation, air brakes on the car, a main operating valve for such brakes associated with such controller, supply and train pipe 80 connections from the brake system of the car to such main valve, auxiliary control valves in such supply and train pipe connections, and means associated with such auxiliary control valves for closing a low resistance path between the terminals of such electromagnetic mechanism when such auxiliary control valves are in a position to permit the operation of such brake mechanism.

27. In combination with a train of cars 95 adapted to be electrically driven, a controller on each of such cars for operating the train, electromagnetic mechanism adapted to be operated by each controller in such operation, air brakes on the train, a main 100 operating valve for such brakes associated with one of such controllers, supply and train pipe connections from the brake system of the train to such main valve, auxiliary control valves in such supply and train pipe connections, and means associated with such auxiliary control valves for closing a low resistance path between the terminals of such electromagnetic mechanism when such auxiliary control valves are in a position 105 to permit the operation of such brakes.

28. In combination with a train adapted to be electrically driven, feeders adapted to supply electric energy to the operating circuit of the motors thereof, switching mechanism on one of the cars of the train for controlling the operating circuit of such motors, conductors extending through the train, an electromagnetic mechanism bridged between two of such conductors and adapted 115 to control such switching mechanism, a controller on another of such cars for operating such electromagnetic mechanism, air brakes on the train, a main operating valve for such brakes associated with such controller, supply and train pipe connections from the brake system of the train to such main valve, auxiliary control valves in such supply and train pipe connections, and a switch operated by one of such auxiliary control 120

valves and adapted to be moved to a position to close a low resistance path between such two conductors when the auxiliary valve operating such switch is in a position 5 to permit the operation of such brakes.

29. In combination with a car adapted to be electrically driven, two controllers for operating the car, a common motor controlling circuit leading to said motor controllers, air 10 brakes on the car, a main operating valve for such brakes associated with each controller, supply and train pipe connections from the brake system of the car to each of such main valves, auxiliary control valves in 15 such supply and train pipe connections, and switching mechanism mechanically operated by such auxiliary control valves and operating upon said motor controlling circuit to render either electric motor controller inoperative 20 when the auxiliary control valves are not in their proper position for the control of the car by that motor controller.

30. In combination with a car adapted to be electrically driven, means for supplying 25 electric energy from feeders to the operating circuit of the motor thereof, switching mechanism for controlling such circuit, two controllers on such car each adapted to operate such switching mechanism, air brakes on the 30 car, a main operating valve for such brakes, supply and train pipe connections from the brake system of the car to such main valve, auxiliary control valves in such supply and train pipe connections, and means associated 35 with such auxiliary control valves for rendering such switching mechanism inoperative by circuits adapted to be closed through the motor controlling circuit, such condition adapted to be produced when such auxiliary 40 control valves are in a condition to permit the operation of such brakes.

31. In an electric motor driven railway train, the combination of a brake system, a 45 plurality of brake controlling devices located at different points on said train, a plurality of electric motor controllers located at differ-

ent points on said train, a common motor control circuit leading to all of the motor controllers, and means positively operated by each brake controlling device to render 50 the motor controlling circuit inoperative whenever the associated brake controlling device is not in a proper running position.

32. In an electric motor driven railway train, the combination of a brake system, a 55 plurality of brake controlling devices located at different points on said train, an electrical motor controller associated with each of the brake controlling devices, a common motor control circuit leading to all of the motor 60 controllers, and switching mechanism positively operated by each of said brake controlling devices and connected with said common motor control circuit for rendering the common motor control circuit inoperative 65 whenever any of the brake controlling devices is not in its proper running position.

33. In an electric motor driven railway train, the combination of a brake system, a 70 plurality of brake controlling devices located on said train, a plurality of electric motor controllers located on said train, a common motor control circuit leading to all of the motor controllers, electromagnetic switching apparatus connected with the common mo- 75 tor control circuit for governing the supply of current to the motor or motors, and switching mechanism directly operated by each of said brake controlling devices and connected with said common motor control 80 circuit for rendering the common motor control circuit impotent to actuate the electromagnetic switching apparatus whenever any of the brake controlling devices is not in its proper running position.

In witness whereof, I hereunto subscribe my name this 27th day of November, A. D., 1907.

ADOLPH H. DAUS.

Witnesses:

EDWIN T. MUNGER,
HARLEY A. JOHNSON.
